(57) **CLAIM**

We claim the ornamental design for a spraying nozzle, as shown and described.

DESCRIPTION

FIG. 1 is a front perspective view of a spraying nozzle of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines depict portions of the spraying nozzle in which the design is embodied that form no part of the claimed design. Additionally, the dot-dash lines denote the boundary of the claim and form no part of the claimed design.
